[57] CLAIM

The ornamental design for a hand held data input terminal for video monitor, as shown and described.

DESCRIPTION

FIG. 1 is a top, front, and right-side perspective view of a hand held data input terminal for video monitor, showing our new design;

FIG. 2 is a front elevational view thereof;

FIG. 3 is a rear elevational view thereof;

FIG. 4 is a left-side elevational view thereof;

FIG. 5 is a right-side elevational thereof;

FIG. 6 is a top plan view thereof; and

FIG. 7 is a bottom plan view thereof.

FIG. 1

FIG. 2

FIG. 6

FIG. 3

FIG. 4

FIG. 5***FIG. 7***
